William L. M. Design. Umbrella Stand

Des. 36

9-13-1845

William L. Miller, New York,
Letters Patent (Design) N°. 36 dated 13th September 1815

The Schedule referred to in these Letters Patent
and making part of the same

To all whom it may concern: Be it known

Dec. 36

that I, William L. Miller, of the city, County & State of New York, have invented a new and useful article of household furniture known as a stand for Hats, Cloaks, Coats, Umbrellas, &c. and I do hereby declare the following to be a full, clear and exact description thereof.

The nature of my invention consists in designing a stand, form or frame, with the necessary hooks and appurtenances upon which clothing & umbrellas may be hung or placed as well as to make a nice and tasteful article of hall furniture of an ornamental structure.

To enable others skilled in the art to make and use my invention, I will proceed to describe its construction.

I form my stand of such height as good taste may dictate, say about seven feet high and place upon it such branches as may be required, as shown in the annexed drawings making a part of this Specification. A. in the drawings is a cavity or pan, in form a scalloped shell, to which is attached the feet upon which it and the whole stand rests. To this attached, by a bolt or otherwise, a perpendicular post, formed in a series of scrolls, shells & leafage, which post may be known as B. in the drawings. C. C. C. C. in the drawings are four circular formed hooks, slightly ornamented, these are intended as rests for umbrellas, so that the water drop into the pan A. D. is also a perpendicular post formed of scrolls, shells & leafage, and joins by bolt or otherwise to B, at about the same juncture as C. does; and on top forms a joint with the circles E. E. E. by bolts or otherwise. E. E. E. are circular curves, upon which hooks may be arranged conveniently for hanging garments, &c. while the centre one formed also by a succession of scrolls, shells & leafage, serves as a frame for a mirror. The hooks may be known as F in the drawings. The next part is also attached to the circle E, on its top part of centre circle, and forms a kind of Gothic arch with finishing scroll on top and two sides. . . . .

leafage, these will be known as one figure H on the drawings.

The entire design is a continued succession of scroll-shell & leafage work, so blended together as to form a tasteful arrangement of architectural ornaments, (and are of the Louis XIV, of France style,) combined with much that is new in that peculiar style of ornaments. I make my stands of cast iron, - (and cast them in separate pieces for convenience,) I then bolt them together with bolts or bolts & nuts, in such manner as not to dis-
face the ornamental designs.

A reference to the drawings will be necessary as it is impossible to give the minutia of each curve, style, cavity - shade &c. In the drawings A is the bottom or pan; B the post; C, the Umbrella hooks; D the upper post; and E is representative of the mirror frame and the side circles; while H is known as the Upper arch with its arms.

What I claim as my own invention and wish to secure by Letters Patent, is the design here represented in the drawings and model, of a stand for placing or hanging Hats, Cloaks, coats, Umbrellas and other articles upon, whether it be made in iron or other metal, composition, wood, or other materials.
